Primary Examiner—Cathy Anne MacCormac[57] **CLAIM**

The ornamental design for a container for use as an aquarium or terrarium, as shown and described.

DESCRIPTION

FIG. 1 is a perspective view of a container for use as an aquarium or terrarium showing our new design; FIG. 2 is a side view, the opposite side being a mirror image thereof;

FIG. 3 is a top plan view;

FIG. 4 is a front elevational view, the opposite view being a mirror image thereof;

FIG. 5 is a bottom plan view;

FIG. 6 is a perspective view of FIG. 1 showing the lid removed;

FIG. 7 is a side view of FIG. 6, the opposite side being a mirror image thereof;

FIG. 8 is a top plan view of FIG. 6;

FIG. 9 is a front elevational view of FIG. 6, the opposite view being a mirror image thereof; and,

FIG. 10 is a bottom plan view of FIG. 6.
